FREDERICK W. PARSONS, OF ELMIRA, NEW YORK, ASSIGNOR TO INGERSOLL-RAND COMPANY, OF JERSEY CITY, NEW JERSEY, A CORPORATION OF NEW JERSEY.

VALVE-SEAT RETAINER.

1,414,665.

Specification of Letters Patent. Patented May 2, 1922.

Application filed January 19, 1922. Serial No. 530,350.

To all whom it may concern:

Be it known that I, FREDERICK W. PARSONS, a citizen of the United States, and a resident of Elmira, county of Chemung, and 5 State of New York, have invented a certain Valve-Seat Retainer, of which the following is a specification, accompanied by drawings.

This invention relates to compressors, but more particularly to valve seat retaining devices for retaining the valve seats and valves 10 in position in the valve openings in the inner wall of the compressor head until the covers and valve securing devices are adjusted on the outer wall or shell of the compressor 15 head.

In a compressor head in which the valves, as for instance plate valves, are arranged radially about the longitudinal axis of the head, difficulty has been experienced in temporarily retaining or supporting the valve 20 seats, carrying valves, in the valve openings on the lower side of the head, while the covers and permanent valve seat holding devices, usually in the form of studs passing 25 through the covers, are being adjusted in position and secured in place.

These valve seats and valves lying below the plane of the horizontal axis of the machine, tend to fall outwardly and downwardly while the covers are being adjusted, and one usual method has been to loosely secure the valves to the valve securing cover studs and adjust the valves and covers at the same time, but with valves of large diameter 35 in particular, the adjustment of the valve seat and valve in its opening may not be accurate, so that leakage or other more serious troubles result. Again the workman cannot see what he is doing, since the cover obscures 40 his view through the outer cover opening in the head, and for this reason he may not set the valve seat accurately in the inner opening.

The primary object of the present invention is to enable the valve seats to be accurately adjusted and temporarily retained in the valve seat openings, particularly in the underside of the inner wall of the head, while the covers are removed, so that the 45 workman can plainly see the adjustment and may afterwards secure the covers and permanent valve securing devices in position without disturbing the adjustment already made. This invention is in some respects 50 a variation and improvement upon the valve

seat retainer disclosed in my Patent No. 1,385,467 granted to me the 26th day of July 1921.

Further objects of the invention will hereinafter appear, and to all of these ends the invention consists of the combination of elements fully described and claimed in this specification and illustrated in one of its preferred forms in the accompanying drawings, in which—

Figure 1 is a diagrammatic longitudinal sectional elevation partly broken away through a compressor head, showing my valve seat retainer in use,

Figure 2 is a side view in perspective of the valve seat retainer, and

Figure 3 is another perspective view of the valve seat retainer.

Referring to the drawings, a type of compressor head A is shown suitable for illustrating the advantages and mode of operation of my device, and I have only chosen to show a portion of a head for simplicity, it being understood however, that the invention may be used with any type of head to which it is found applicable. The head is adapted to be fitted to a cylinder A' having a reciprocating piston A².

The head illustrated is provided with the usual valve seat openings B in the inner wall C, adapted to receive the valve seats D in this instance carrying plate valves, of any suitable type. The openings B, as shown, are provided with the rabbeted or counterbored portions E, adapted to receive the gaskets E' for seating the flanges F of the valve seats D. The invention applies equally to either inlet or discharge valves, and in this instance, for illustrative purposes, the upper valve is indicated as an inlet valve and the lower valve is shown as a discharge valve. The outer wall G of the head is provided with openings H corresponding to the openings B and the usual covers J, of which only one is shown, are provided for closing the outer openings after the valve seats and valves are in place. Adjustable holding devices, preferably in the form of studs K pass through each cover for securing the valve seats in final position and cover holding means, which may be in the form of studs L are provided on the outer wall.

In order to temporarily maintain the valve seats D in the openings B in the underside of the head, with the covers removed,

I have provided a valve retainer in the form of a bow shaped spring clip L' of sheet metal, which may be carried in any suitable or convenient manner by the valve structure, 5 and is adapted to engage the outer wall of the compressor head for retaining the valve seat in position in the valve seat opening until the cover and valve securing devices are adjusted. The spring retainer may be 10 provided with a central aperture O adapted to be placed over the center bolt P of the valve, after which a screw handle Q is screwed over the center bolt P. The valve seat is adjusted in position by means of the 15 handle Q care being taken not to dislodge the gasket E'. As the valve seat is adjusted, the hooked ends R of the valve seat retainer will slip into place and engage the edge of the outer opening H for the cover, and will 20 thus retain the valve seat in position after the handle Q is removed. The retainer L' remains in position in the head and a cover J may be adjusted in position, and the stud K or valve securing device is screwed down 25 against the center bolt P to hold the valve seat permanently in position in the usual manner.

In order to save metal, and yet procure a valve seat retainer having tapered ends S, 30 producing increased resiliency, the strips from which the retainers are made are preferably cut from a sheet of metal in such manner that the sides a and b are parallel, and the sides c and d are parallel. Assume 35 for instance that the side a is the original end of a sheet of metal from which the strips were cut, it will be observed that the side b is cut parallel to the side a, and then in order to make the tapered ends, the sides c

and d are cut parallel, and yet the hooked 40 ends R lie on the longitudinal axis of the clip, one opposite the other. Obviously, the clip may be cut or otherwise constructed in any suitable or desired manner.

I claim:

1. In a compressor, a compressor head having a valve seat opening in its inner wall adapted to receive a valve seat carrying a valve, the outer wall of the head having a corresponding opening adapted to be closed 50 by a cover carrying an adjustable valve securing device, and a valve retainer in the form of a bow shaped spring clip carried by the valve structure and adapted to engage the outer wall of the compressor head and re- 55 main in the head for retaining the valve seat in position in the valve seat opening until the cover and valve securing device are adjusted.

2. In a compressor, a compressor head 60 having a valve seat opening in its inner wall adapted to receive a valve seat carrying a valve, the outer wall of the head having a corresponding opening adapted to be closed 65 by a cover carrying an adjustable valve securing device, and a valve retainer in the form of a bow shaped spring clip having hooked ends, said spring retainer being carried by the valve structure and the hooked ends being adapted to engage the edge of 70 the opening in the outer wall of the compressor head and remain in the head for retaining the valve seat in position in the valve seat opening until the cover and valve securing device are adjusted.

In testimony whereof I have signed this specification.

FREDERICK W. PARSONS.
